AIRCRAFT SUSTAINING ROTOR

James Allan Jamieson Bennett, Esher, England, assignor, by mesne assignments, to Autogiro Company of America, a corporation of Delaware

Application March 31, 1938, Serial No. 199,150.
Renewed July 13, 1939. In Great Britain April 6, 1937

18 Claims. (Cl. 244—18)

This invention relates to aircraft sustaining rotors, and is particularly concerned with the type of rotor incorporating one or more blades which are articulated to a common generally upright hub, the blades being arranged to provide for autorotative actuation in flight.

Still further, the invention has particular reference to rotors of this general type which are also arranged to be driven on the ground prior to take-off in order to store kinetic energy in the rotor, the blade pitch angle at this time being at a low, preferably zero, value, so that upon disconnection of the drive and raising of the pitch angle, a high initial thrust is secured to effect direct or jump take-off.

The invention contemplates a blade articulation and rotor driving arrangement for the above purpose, and in considering some of the advantages it should be noted that in certain prior constructions change of pitch as between the zero and flight positions is provided for by employing a blade pivot the axis of which is inclined upwardly and outwardly with respect to the longitudinal blade axis, so that upon application of the driving torque, the blade assumed a lagging and low pitch position, and, upon cessation of the driving torque, the blade advanced to the radial or to a leading position in which the pitch was increased. Such a construction is disclosed in copending application of Juan de la Cierva, Serial No. 738,349, filed August 3, 1934, corresponding to British Patent No. 420,322, accepted November 29, 1934. As may be seen in that case, the inclined pivots may desirably be provided with lagging and leading stops limiting the range of pitch change movement.

In arrangements of said prior type, if the oblique pivot is inclined at an extreme acute angle to the blade and is utilized during normal flight operation to accommodate lag and lead displacements of the blade, the blade oscillations are unstable, at least in the absence of damper devices.

The present invention provides blade pivots including a flapping or delta pivot which is acutely angled with respect to the longitudinal blade axis at the leading side thereof to provide for pitch change of the blade during flapping, and also a drag or alpha pivot having its axis so positioned as to produce a stable condition, the lag and lead displacements of the blade about this pivot being aerodynamically damped.

The invention further provides a drive mechanism having a driving element extended to engage a blade pivot part in such manner as to ensure that the blade will move on the alpha pivot axis to a low or zero pitch position during driving.

How the foregoing objects and advantages are attained, will appear more fully in the following description making reference to the accompanying drawings, in which—

Figure 1 is a top plan view of a rotor hub and the root ends of three blades articulated thereto by means of pivots constructed in accordance with the invention;

Figure 2 is a vertical sectional view of the structure shown in Figure 1; and

Figure 3 is a view taken substantially as indicated by the section line 3—3 applied to Figure 1.

For purposes of control of the craft in flight, the rotor here shown is mounted for tilting in all directions by means of a gimbal ring 5 adapted to be trunnioned as at 6—6 on any suitable rotor hub support or fixed pylon structure. The hub is carried within the ring 5 by means of additional trunnions 7—7, the axis of which is at right angles to the axis of the trunnion 6—6. The manual control for rotor tilting need not here be shown as suitable control for this purpose appears in the copending Cierva application above referred to.

The trunnions 7—7 carry downwardly and inwardly extended rotor hub supports 8—8 which serve to mount the non-rotative bearing housing 9 in which a rotative hub spindle 10 is journaled as by bearings 11. A block or hub proper 12 is connected to the upper end of the rotative spindle 10, this hub block having three radially extended flapping pivots 13 which cooperate respectively with the several blades, the root end portion of the blade spars appearing at 14 in Figure 1.

Each spindle or flapping pivot 13 serves to carry the intermediate member 15 which is journaled thereon, a thrust bearing 16 interposed between the member 15 and the abutment 17 serving to take loads axially of the flapping pivot 13.

The intermediate member 15 for each blade carries pivot 18 (the alpha or drag pivot) on 40 which the gooseneck blade connecting member 19 is journaled, the latter being in turn connected with the blade spar 14. The several parts just described are so positioned as to bring the longitudinal axis of the blade to a position in 45 which it substantially intersects the rotational axis of the hub.

Inspection of the several figures of the drawings will show that the axis d—d of the flapping or delta pivot 13, when viewed in plan, makes 50 an acute angle with the longitudinal axis of the blade B—B at the leading edge thereof, the direction of rotation being indicated by an arrow. It will also be noted from Figure 1 that the axis d—d is slightly offset from the axis of rotation 55

of the hub, and that the axis $a-a$ of the alpha or drag pivot is offset from the hub further than the axis $d-d$.

Still further, as best seen in Figure 3, the axis $a-a$ of the alpha or drag pivot, when projected on a plane perpendicular to the blade axis, makes an acute angle with the hub axis $R-R$. A secondary inclination of the alpha axis appears when viewing the rotor in plan, as in Figure 1, in which it will be seen that the axis of this pivot makes an acute angle with the longitudinal blade axis $B-B$ at the trailing side thereof.

Turning now to the driving mechanism, a centrally located drive shaft 20 is connected by means of universal joint 21 with the lower part 22 of a disengageable clutch, the upper part 23 of which is disposed at the lower end of a hollow shaft 24 serving as a guide for longitudinal movement of the sleeve 25 which projects upwardly from the lower part of the clutch 22. Shaft 24 extends upwardly through the rotative spindle 10, and toward its upper end carries a series of rollers 26 adapted to engage respectively with arms 27 formed on the root end fittings 19 of the several blades. The operation of this drive and its cooperation with the pivot axes is described hereinafter.

It may first be noted that because of the inclination of the alpha pivot axis with respect to the longitudinal axis of the blade, as seen in Figure 2, lagging displacement of the blade about this axis decreases the pitch and leading displacement increases the pitch. Therefore, upon application of the driving torque to the rotor hub, even without the provision of special drive mechanism, the resulting lag of the blade produces a decrease in pitch. However, in order to ensure that the blade shall be held against the lagging stop and thus at zero pitch, drive mechanism of the character described above is preferably employed, this drive mechanism transmitting torque directly to the blade root connecting members in a sense tending to move the blade about the alpha pivot in a lagging direction. By arrangement of driving elements in this way, the blade is retained against the lagging stop (low or zero pitch position) even against the centrifugal restoring moment set up at high R. P. M. It may here be noted that some features of a drive mechanism of this general type are disclosed in my copending application Serial No. 205,352, filed April 30, 1938, corresponding to British application No. 12,398, filed April 30, 1937.

By virtue of the inclination of the alpha pivot axis when projected on a plane perpendicular to the blade axis (i. e. making an acute angle with the axis of the hub), the lag and lead movements of the blade in flight operation produce components of motion in the flapping sense and therefore are aerodynamically damped, thus overcoming instability heretofore encountered in some arrangements of this general type.

The provision of an obliquely angled flapping pivot in combination with the alpha pivot inclination above discussed, is of advantage since, in purely leading and lagging displacements of the blade, the flapping component of the movement on the alpha pivot is compensated by a flapping displacement of opposite sign on the delta pivot which because of the obliquity of the latter produces a variation of blade angle, a decrease of blade angle by pivotation about the delta pivot being associated with a lagging displacement about the alpha pivot.

The inclinations of the delta and alpha pivot axes as described, and the mounting of the blade, provide for substantially zero blade pitch when the blade is against the lagging stop and extended in a substantially horizontal position. Maintenance of the substantially horizontal position is assured at high R. P. M. by the fact that the centrifugal force is large compared with the weight of the blade, and further by the fact that the flapping movement is stabilized by the inclination of the delta axis in a sense causing the blade angle to decrease with upward flapping, and vice versa.

The inclination of the delta axis in the direction stated has still other advantages, including improvement in smoothness of flight operation, especially in rough air, and also improvement with respect to the "lift-vector-shift characteristic", as disclosed in copending application Serial No. 199,151, filed March 31, 1938, issued March 20, 1940 as Patent No. 2,192,492, corresponding to British application No. 9801, filed April 6, 1937.

I claim:

1. In an aircraft sustaining rotor having a hub and a blade, a flapping pivot for connecting the blade with the hub and obliquely inclined with respect to the blade axis to provide for decrease of blade pitch upon upward flapping movement thereof and increase of blade pitch upon downward flapping movement, and a drag pivot for the blade positioned to provide for pitch change movement thereof, the axis of the drag pivot, when projected on a plane perpendicular to the blade axis, making an acute angle with the axis of the hub.

2. In an aircraft sustaining rotor having a hub and a blade, a flapping pivot for connecting the blade with the hub and obliquely inclined with respect to the blade axis to provide for decrease of blade pitch upon upward flapping movement thereof and increase of blade pitch upon downward flapping movement, and a drag pivot for the blade positioned to provide for pitch change movement thereof, the axis of the drag pivot being inclined upwardly and rearwardly of the blade.

3. In an aircraft sustaining rotor having a hub and a blade, a flapping pivot for connecting the blade with the hub and obliquely inclined with respect to the blade axis to provide for decrease of blade pitch upon upward flapping movement thereof and increase of blade pitch upon downward flapping movement, a drag pivot for the blade positioned to provide for pitch change movement thereof, the axis of the drag pivot, when projected on a plane perpendicular to the blade axis, making an acute angle with the axis of the hub, and drive mechanism for the rotor connected with a blade pivot part in such manner as to cause the blade to move about the axis of the second pivot in a direction to decrease the pitch thereof.

4. In an aircraft sustaining rotor incorporating a hub and a blade, pivot mechanism for connecting the blade to the hub including a pivot providing for upward and downward flapping movement of the blade and, when viewed in plan, arranged with its axis at an acute angle to the longitudinal axis of the blade at the leading side thereof, and a second pivot axis accommodating lag and lead movements of the blade, which second pivot axis, when viewed in plan, makes an acute angle with the longitudinal blade axis at the trailing edge thereof.

5. In an aircraft sustaining rotor incorporating

a hub and a blade, pivot mechanism for connecting the blade to the hub including a pivot providing for upward and downward flapping movement of the blade and, when viewed in plan, arranged with its axis at an acute angle to the longitudinal axis of the blade at the leading side thereof, and a second pivot axis accommodating lag and lead movements of the blade, which second pivot axis, when viewed in plan, makes an acute angle with the longitudinal blade axis at the trailing edge thereof, the axis of the second pivot being inclined upwardly and rearwardly of the blade.

6. In an aircraft sustaining rotor incorporating a hub and a blade, pivot mechanism for connecting the blade to the hub including a pivot providing for upward and downward flapping movement of the blade and, when viewed in plan, arranged with its axis at an acute angle to the longitudinal axis of the blade at the leading side thereof, and a second pivot axis accommodating lag and lead movements of the blade, which second pivot axis, when viewed in plan, makes an acute angle with the longitudinal blade axis at the trailing edge thereof, both of said pivot axes being offset from the axis of the hub.

7. In an aircraft sustaining rotor incorporating a hub and a blade, pivot mechanism for connecting the blade to the hub including a pivot providing for upward and downward flapping movement of the blade and, when viewed in plan, arranged with its axis at an acute angle to the longitudinal axis of the blade at the leading side thereof, a second pivot axis accommodating lag and lead movements of the blade, which second pivot axis, when viewed in plan, makes an acute angle with the longitudinal blade axis at the trailing edge thereof, and driving mechanism for the rotor including a driving connection extended to engage a part movable with the blade about the second pivot axis and providing for movement of the blade about said second pivot axis to a reduced pitch position upon application of the drive.

45 8. In an aircraft sustaining rotor having a hub and a blade, pivot mechanism connecting the blade with the hub including two pivots both obliquely inclined with respect to the longitudinal axis of the blade to provide for pitch change movement, the axes of said two pivots, when viewed in plan, making acute angles with the longitudinal axis of the blade, one at the leading edge thereof and the other at the trailing edge thereof, and at least one of said axes lying approximately in a plane perpendicular to the hub axis.

9. In an aircraft sustaining rotor having a hub and a blade, pivot mechanism connecting the blade with the hub including two pivots both obliquely inclined with respect to the longitudinal axis of the blade to provide for pitch change movement, the axes of said two pivots, when viewed in plan, making acute angles with the longitudinal axis of the blade, one at the leading edge thereof and the other at the trailing edge thereof, at least one of said axes lying approximately in a plane perpendicular to the hub axis, and drive mechanism for the rotor cooperating with a blade pivot part to deliver torque thereto in a sense providing for decrease of blade pitch about one of said pivots upon application of the driving torque.

10. In an aircraft sustaining rotor having a hub and a blade, pivot mechanism for connecting the blade with the hub including a flapping

pivot providing primarily for movement of the blade in a direction transverse its mean rotative path of travel, and a second pivot the axis of which, when viewed in plan, is acutely angled with respect to the longitudinal blade axis at the trailing edge thereof and which is inclined upwardly and rearwardly with respect to the blade, the second pivot providing for lagging and leading displacement of the blade from a true radial position.

11. In an aircraft sustaining rotor having a hub and a blade, a flapping pivot for connecting the blade with the hub and obliquely inclined with respect to the blade axis to provide for decrease of blade pitch upon upward flapping movement thereof and increase of blade pitch upon downward flapping movement, and a drag pivot for the blade positioned to provide for pitch change movement thereof, the axis of the drag pivot being spaced further from the axis of the hub than the axis of the flapping pivot and, when projected on a plane perpendicular to the blade axis, making an acute angle with the axis of the hub.

12. In an aircraft sustaining rotor having a hub and a blade, a flapping pivot for connecting the blade with the hub and obliquely inclined with respect to the blade axis to provide for decrease of blade pitch upon upward flapping movement thereof and increase of blade pitch upon downward flapping movement, and a drag pivot for the blade positioned to provide for pitch change movement thereof, the axis of the drag pivot being spaced further from the axis of the hub than the axis of the flapping pivot and inclined upwardly and rearwardly of the blade.

13. In an aircraft sustaining rotor having a hub and a blade, a flapping pivot for connecting the blade with the hub and obliquely inclined with respect to the blade axis to provide for decrease of blade pitch upon upward flapping movement thereof and increase of blade pitch upon downward flapping movement, a drag pivot for the blade positioned to provide for pitch change movement thereof, the axis of the drag pivot being spaced further from the axis of the hub than the axis of the flapping pivot and when projected on a plane perpendicular to the blade axis, making an acute angle with the axis of the hub, and drive mechanism for the rotor connected with a blade pivot part in such manner as to cause the blade to move about the axis of the second pivot in a direction to decrease the pitch thereof.

14. In an aircraft sustaining rotor having a hub and a blade, pivot mechanism for connecting the blade with the hub including a flapping pivot providing primarily for movement of the blade in a direction transverse its mean rotative path of travel, and a second pivot the axis of which, when viewed in plan, is acutely angled with respect to the longitudinal blade axis at the trailing edge thereof and which is inclined upwardly and rearwardly with respect to the blade and is spaced further from the axis of the hub than the axis of the flapping pivot, the second pivot providing for lagging and leading displacement of the blade from a true radial position.

15. In an aircraft sustaining rotor, a hub, three blades positioned with their longitudinal axes radiating from the hub, pivot means for connecting the blades with the hub including pivot parts clustered around the hub in positions intermediate the longitudinal axes of the blades, the pivot means for each blade including a flapping pivot the axis of which when viewed in plan makes an

acute angle with the longitudinal axis of the blade and a drag pivot the axis of which is positioned to provide a component of blade movement in the pitch-change sense, the axis of the flapping pivot lying close to a position of coincidence with the longitudinal axis of an adjacent blade but being slightly offset from the hub axis, and the axis of the drag pivot being offset from the hub axis a distance greater than the offset of the flapping pivot axis.

16. In an aircraft sustaining rotor having a hub and a blade, pivot mechanism connecting the hub with the blade including a pivot having its axis positioned to provide primarily for flapping movement of the blade, and a pivot having its axis positioned to provide primarily for lag-lead movement of the blade, the flapping pivot axis, when viewed in plan, making an acute angle with the longitudinal axis of the blade at the leading side of the latter, the axes of both of said pivots being offset from the hub axis, and the lag-lead pivot axis being offset from the hub axis to an extent greater than the flapping pivot axis.

17. In an aircraft sustaining rotor having a hub and a blade, pivot mechanism connecting the hub with the blade including a pivot having its axis positioned to provide primarily for flapping movement of the blade, and a pivot having its axis positioned to provide primarily for lag-lead movement of the blade but obliquely inclined with respect to the longitudinal axis of the blade to

provide a component of blade movement in the pitch-change sense, the flapping pivot axis, when viewed in plan, making an acute angle with the longitudinal axis of the blade at the leading side of the latter, the axes of both of said pivots being offset from the hub axis, and the lag-lead pivot axis being offset from the hub axis to an extent greater than the flapping pivot axis.

18. In an aircraft sustaining rotor having a hub and a blade arranged with its longitudinal axis substantially intersecting the hub axis, pivot mechanism for connecting the blade with the hub including a flapping pivot offset forwardly of the longitudinal blade axis, the axis of which pivot, when viewed in plan, makes an acute angle with the longitudinal blade axis at the leading side thereof, and a drag pivot operatively interposed between said flapping pivot and the blade, the drag pivot being obliquely inclined with respect to the longitudinal blade axis and providing for decrease of blade pitch upon lagging movement of the blade and increase of pitch upon leading movement thereof, and driving mechanism for the rotor including a driving element movable with respect to and cooperating with a part of the blade pivot mechanism for urging the blade to move upon one of said pivots in a sense effecting decrease of blade pitch upon application of torque.
